Scranton, Pa., a corporation of Delaware

Application March 19, 1946, Serial No. 127,667

Term of patent 14 years

(Cl. D29—23)

To all whom it may concern:

Be it known that I, William Taylor Jones, a citizen of the United States, residing at 440 S. Main Ave., Scranton, in the county of Lackawanna and State of Pennsylvania, have invented a certain new, original, and ornamental Design for a Holy Water Font, of which the following is a specification, reference being had to the accompanying drawing, forming part thereof.

I claim:

The ornamental design for a holy water font, as shown.

WILLIAM TAYLOR JONES.
